* cited by examiner

Primary Examiner — Leanne Was-Englehart(74) *Attorney, Agent, or Firm* — Sand, Sebolt & Wernow Co., LPA(57) **CLAIM**

The ornamental design for a T square, as shown and described.

DESCRIPTION

FIG. 1 is a front, top, right side isometric perspective view of a T square in accordance with our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The drawings contain a symbolic break. The portion between the break lines forms no part of the claimed design. The broken lines illustrate portions of the T square which form no part of the claimed design.
